Atty.

UNITED STATES PATENT OFFICE.

WILLIAM J. BARBER, OF DELPHOS, OHIO, ASSIGNOR TO THE E. & N. MANUFACTURING COMPANY, OF DELPHOS, OHIO, A CORPORATION OF OHIO.

DUST MOP.

Application filed October 15, 1924. Serial No. 743,693.

This invention relates to dust mops of the type having a swab, the floor engaging portion of which is composed of loosely hung strands of yarn and has for its object to provide a mop of simple and durable construction which is efficient in operation and which can be manufactured cheaply.

A more specific object of the invention is to provide a yarn and fabric swab adapted to be detachably secured to a supporting frame attached to the end of a mop handle and formed wholly of fabric and yarn so that it may be readily detached and washed.

A further object is to provide a fabric and yarn swab which is so formed and so connected to its supporting frame that it cannot become twisted or turned out of proper floor engaging position on the frame. In accordance with the present invention the main body of yarn is secured around the marginal portion of a fabric body in such manner that the yarn retaining and enclosing strip projects above the fabric body, the holding frame is formed to fit upon the central fabric portion of the body and within the marginal yarn retaining portion and the body is secured in place upon the foot piece by drawing the marginal yarn retaining portion inwardly over the edge portions of the frame so that the fabric body is stretched across the under side of the frame and the marginal yarn retaining portion is securely held against creeping on the frame and forms a buffer or cushion along the edge of the frame to prevent marginal ring of furniture in the use of the mop.

A further object is to provide a swab supporting frame which is so formed that it will accommodate itself to shrinkage of the fabric of the swab such as may be caused by washing.

A further object is to so mount the swab upon the handle that when the mop is shaken there will be a jarring impact of the body against the handle of the mop to facilitate the dislodgment of dust.

With the above and other objects in view the invention may be said to comprise the device as illustrated in the accompanying drawings hereinafter described and particularly set forth in the appended claims, together with such variations and modifications thereof as will be apparent to one skilled in the art to which the invention appertains.

Reference should be had to the accompany-

ing drawings forming a part of this specification in which Fig. 1 is a top plan view of the 55 mop; Fig. 2 is a longitudinal central section through the mop; Fig. 3 is a vertical transverse section; Fig. 4 is a bottom plan view of the mop; Fig. 5 is a plan view of the swab supporting frame carried by the handle. 60

The present invention relates to a yarn carrying body and the means for securing same to the handle of the mop. The handle 1 has a channel-shaped attaching plate 2 riveted upon the end thereof and the attaching plate 2 65 is pivotally connected to a channel-shaped attaching member 3 by means of a horizontal pivot pin 4. The attaching member 3 carries a flat substantially rigid swab supporting frame 5, preferably made of stiff wire, which, 70 as best shown in Fig. 5, has outwardly bent laterally projecting portions 5^a and forwardly of the projections 5^a has parallel portions 5^b secured within the channel attaching member 3 by means of tongues 3^a struck from the upwardly extending flanges of the attaching member. Forwardly of the attaching member 3 the wire forming the sides of the frame is bowed outwardly at 5^c and at the forward end the free ends of the wire are bent outwardly and back upon themselves to form lateral projections 5^d, the ends 5^e of the wire being in alignment and spaced apart. The rear end portion of the wire frame and the portion thereof held within the attaching 75 clip 3 forms the rear end of the frame which is substantially rigid. The ends of the wire projecting forwardly from the clip 3 form resilient spaced arms which can be sprung apart or pressed together to accommodate 80 yarn carrying bodies of different sizes as will be hereinafter more fully explained.

The body portion of the swab is formed by a flat piece of fabric 6 preferably of double thickness which corresponds substantially in 85 length and width to the wire frame 5. The body portion 6 may have strands of yarn 7 sewed upon the underface thereof but the main body of yarn 8 is secured around the edges of the body member 6. Each of the 90 strands of the yarn 8 is doubled upon itself and passes around a retaining cord 9, the looped portion of the yarn enclosing the cord 9 being secured within a fabric retaining strip 10 which is folded over the looped yarn and 95 has its edges sewed together through the yarn

below the cord 9 along the seam 11, the cord 9 being secured adjacent the center of the strip 10 by a transverse seam 12 so that it cannot be pulled out. In the manufacture 5 of the swab the yarn is hung over the cord 9 and the retaining strip 10 is sewed in place thereon prior to the attachment to the body portion 6. One edge 13 of the strip 10 projects beyond the seam 11, and the projecting 10 portion 13 is sewed to the marginal edges of the body portion 6, the strip 10 being of a length to completely encircle the body portion 6. A piece of fabric 14 overlies the forward portion of the fabric body 6 and is sewed 15 thereto along the edges at the sides and front end to form a pocket for the forward end of the frame 5. The retaining strip 10 carrying the main body of yarn 8 is so secured to the body portion 6 that the cord retaining seam 20 12 is at the forward end of the body and the free ends of the strip 10 come together at the rear end of the body, the free ends of the cord 9 projecting through the enclosing strip 10 at the joined end and forming a draw string 25 by means of which the yarn retaining portion 10 may be drawn inwardly.

To fasten the fabric and yarn swab to the frame 5, the forward end of the frame is inserted within the pocket 14 and the rear end 30 thereof forced down within the marginal yarn retaining portion at the rear end of the swab. Since the frame 5 conforms substantially to the flat fabric body 6 in length and in width at the extreme front and rear ends, it will be 35 obvious that the frame fits snugly within the marginal yarn retaining portion 10, the forward resilient arms of the frame being preferably sprung outwardly to fit tightly in the pocket 14 and to stretch the fabric body 6 so 40 that it is held flat against the underside of the frame. After the frame has been put in place within the yarn retaining portion 10, the draw string 9 may be pulled tight and tied, drawing the marginal yarn retaining 45 portion 10 inwardly from the front and rear ends of the frame so as to securely fasten the yarn carrying body to the frame. Since the swab is formed wholly of fabric and yarn it can be readily washed and if there is any 50 shrinking in the fabric due to the washing the resilient forward end of the frame when inserted within the pocket 14 will be sprung together sufficiently to accommodate itself to the shrunken body. The pivotal connection 55 between the frame and handle is preferably between the rear end and the longitudinal center thereof so that the floor engaging body has a tendency to tilt forwardly on the pivot and in pushing the mop over the floor pressure 60 is exerted uniformly upon the mop. The pivotal connection between the handle and frame intermediate the ends thereof has a further advantage that in shaking the mop to dislodge dust therefrom, the mop body has a 65 jarring impact against the handle making it

unnecessary to strike the handle to obtain the jar necessary to dislodge the dust.

Having described my invention, I claim—

1. A mop comprising a swab formed of a flat fabric body having a retaining strip for 70 yarn extending around the margin thereof, a body of loosely hung yarn strands having portions enclosed in said retaining strip, said retaining strip and the portions of the yarn strands therein projecting above said fabric 75 body to provide a pocket in the swab, a frame received in said pocket, said frame having a thickness less than the height of said strip, and means connected to said yarn enclosing strip for drawing the same over the top of 80 said frame to hold the frame between said strip and fabric body and a handle secured to said frame.

2. A mop comprising a swab formed of an elongated flat fabric body having a retaining 85 strip for yarn extending around the margin thereof, a body of loosely hung yarn strands having portions enclosed in said retaining strip, said retaining strip and the portions of the yarn strands enclosed in said retaining 90 strip projecting above the fabric body to provide a pocket in the swab, a fabric strip extending across the top of the fabric body at one end to form a retaining pocket, an elongated frame substantially fitting in the pocket 95 formed by the marginal yarn retaining strip and of less depth than said marginal strip, said frame having one end portion extending into said retaining pocket, means for drawing said marginal yarn retaining strip over the 100 top of the frame at the opposite end thereof to secure the swab to the frame, and a handle pivoted to the frame intermediate the ends thereof.

3. A mop comprising a swab formed of an elongated flat fabric body having a retaining strip for yarn extending around the margin thereof, a body of loosely hung strands of 105 yarn having portions enclosed in said strip, said retaining strip with the portions of the 110 yarn strands therein projecting above the fabric body to provide a pocket in the swab, a fabric strip extending across said fabric body at one end to form a retaining pocket, an elongated frame formed of resilient wire and 115 having an end portion normally wider than said retaining pocket and formed of separate laterally flexible arms adapted to extend into said retaining pocket and to exert spring pressure along opposite edges of said pocket, means for drawing said yarn retaining strip over the opposite end of said frame to secure 120 the same to the swab, and a handle pivoted to said frame intermediate the ends thereof.

4. A mop comprising a swab formed of a flat fabric body having a retaining strip for 125 yarn extending around the margin thereof, said retaining strip supporting a body of absorbent strands with the strands completely surrounding the fabric body and the strip 130

projecting thereabove to provide a pocket in the swab, a frame received in the pocket of the swab, said frame having a thickness less than the height of the strip, a draw-string connected to said strip for drawing the same

tightly against the bottom of the frame, whereby the frame is securely held between said strip and said fabric body. 10

In testimony whereof, I hereunto affix my signature.

WILLIAM J. BARBER.
